[57] CLAIM

We claim the ornamental design for a simulated walking device, as shown.

DESCRIPTION

FIG. 1 is a top, front and left side perspective view of a simulated walking device showing our new design;

FIG. 2 is a left side elevational view thereof;

FIG. 3 is a front elevational view thereof;

FIG. 4 is a top plan view thereof;

FIG. 5 is a right side elevational view thereof; and,

FIG. 6 is a rear elevational view thereof.

The appearance of the bottom forms no part of the claimed design.
